LETTER WALLET AND BILLFOLD

Martin E. Trolle, St. Paul, Minn., assignor to
Brown & Bigelow, St. Paul, Minn., a corpora-
tion of Minnesota

Application January 24, 1938, Serial No. 186,563

2 Claims. (Cl. 150—35)

My invention relates to an improvement in letter wallet and billfold wherein it is desired to provide a letter wallet having a removable inner pocket which may if desired be used as a billfold.

Letter wallets have been constructed for a number of years for the purpose of carrying letters and envelopes to prevent damage thereto or the creasing or bending thereof. These letter files are ordinarily formed of a flat piece of leather or similar material centrally folded upon itself and having one edge adjacent the folded edge sewed together. This provides a file with two open sides one side of which is opposite the folded edge, and the other side of which forms the top of the file to permit envelopes of larger size than the file to extend through this open edge. The present invention embodies a construction substantially of this sort, but provides in addition thereto a removable inner compartment in which papers of a more confidential nature or currency may be contained.

It is a purpose of the present invention to provide a letter file of substantially the usual type and to attach thereto an inner file adapted to contain confidential papers or money. This inner file is removably secured within the letter file so that it may be removed for facilitating the placing of papers and the like into the same or may be removed entirely for a period of time and used as a billfold.

It is a purpose of the present invention to provide a letter file having an inner file attached thereto by a pivotal means so that the inner file may be pivoted out of the letter file when it is desired to insert or remove papers from the inner file. This pivotal means is so positioned as to permit the inner file to be swung almost entirely out of the outer file so that all the pockets in the same will be readily accessible throughout their entire length for the insertion or removal of such papers. Thus in ordinary use it is not necessary to remove the inner file from the outer file as both files may be used while still attached together. At the same time, however, the inner file when in normal position is entirely enclosed within the outer file.

It is a feature of the present invention that the inner file is readily accessible and may be easily used while at the same time the pockets in the inner file into which papers may be inserted all open toward the folded side of the outer letter file. Thus the papers within the inner billfold portion may be held in place within the billfold with little danger of having these papers lost or misplaced, as such papers as are

inserted into the inner billfold portion cannot be taken therefrom unless the billfold is swung out into open position.

These and other objects and novel features of my invention will be more clearly and fully set forth in the following specification and claims.

In the drawing forming a part of my application:

Figure 1 is a front elevation view of my wallet and billfold in closed position.

Figure 2 is a similar view illustrating a portion of the outer cover of the billfold broken away to disclose the inner construction thereof.

Figure 3 is an edge view of the wallet and billfold illustrated in Figures 1 and 2.

Figure 4 is a cross-sectional view in enlarged size of the wallet and billfold taken on the line 4—4 of Figure 1.

Figure 5 is a longitudinal section taken on the line 5—5 of Figure 1.

Figure 6 is a cross-sectional view through the outer letter wallet with the inner billfold removed, the section being taken substantially along the line 4—4 of Figure 1.

Figure 7 is a side elevation view of the billfold removed from the letter wallet.

Figure 8 is a cross-sectional view through the billfold taken on the line 8—8 of Figure 7.

The letter wallet and billfold A comprises two separable parts, an outer letter wallet B, and an inner billfold C. The letter wallet B is attached to the billfold C by means of a snap fastener 10 in a manner which will be later more clearly described.

The letter file B comprises a body 11 formed of a flat sheet of leather, imitation leather, or other suitable material folded along one edge 12. As may be seen in Figures 2, 4, 5, and 6, of the drawing, the body 11 is provided with inturned marginal edges 13 which are preferably folded back against the body 11 and adhered thereto. Rows of stitching 14 extend through the body 11 and through the marginal edges 13 along the upper edge 15 of the letter wallet and along the longitudinal edge 16 thereof opposite the folded edge 12. As may be seen in Figures 1, 2, and 5 of the drawing, a row of stitching 17 extends through both sides of the body 11 and through oppositely disposed flanges 13 along the lower edge 19 of the letter wallet, thus closing this lower edge to prevent papers inserted within the letter wallet from falling through this lower edge 19.

The letter file thus formed is similar to letter files which have previously been constructed for

the purpose of containing papers to be carried. The papers are held in place by the joined edges 12 and 19, but may be of any size as the edges 15 and 16 are entirely open. One portion of a snap fastener 10 is positioned through the body 11 near the lower corner of the letter wallet where the lower edge 19 and the outer edge 16 meet. This portion of the fastener enables the billfold to be connected to the wallet at this point.

10 The billfold C is constructed as best illustrated in Figures 4, 5, 7, and 8 of the drawing. This billfold C is formed of a flat sheet of leather or similar material 20 which is folded at 21 to form opposite sides 22 and 23. The side 23 is shown shorter than the side 22 providing a pocket 24 in one side of the device. The body 20 is provided with inturned edges 25 extending along the edge 26 thereof opposite the folded edge 21 and along the parallel edge 27 of the side 23. These 20 marginal edges are adhered in folded position as disclosed in Figure 8.

Between the sides 22 and 23 of the body 20 I provide a flat partition sheet 29 extending closely adjacent the folded edge 21 and projecting to a point slightly spaced from the opposite edge 26. This latter edge is marginally folded at 30 and adhered to the sheet 29 to present a double edge on this sheet.

The body 20 is provided on one side with extended marginal edges 31 best seen in Figures 5 and 7 of the drawing, which fold over the ends of the billfold to seal these ends and which are held in this folded position by stitching 32. This stitching 32 extends through both sides of the body 20, namely, the sides 22 and 23, through the partition sheet 29 and through the marginal edge 31. The ends of the billfold are thus securely sealed.

A portion of a snap fastener 10 cooperable with the portion secured to the letter wallet B is attached to the side 23 of the body 20 near the juncture of the folded edge 21 of the billfold and the lower edge of the same. By this means the billfold C may be pivotally and removably attached to the letter wallet B and may be contained entirely within the same as illustrated in Figure 1 of the drawing or may be swung into open position as indicated by the dotted outline in Figure 1 of the drawing.

50 From the foregoing description it will be clear

that when the billfold is swung into closed position as indicated in Figure 4 of the drawing, the pockets formed between the outer sheet 23 and the partition sheet 29 and between the partition sheet 29 and the side 22, face inwardly toward the folded edge 12 of the wallet. Thus papers supported by the billfold cannot be disengaged from the billfold while the same is in place as illustrated in Figure 4. However, when the file C is pivoted into the dotted outline position illustrated in Figure 1 of the drawing, the pockets are openly accessible, and papers may be inserted or removed without handicap. Whether or not the billfold is in place, the papers contained in the letter wallet will not be effected and may be removed at will. If desired, the inner billfold C may be entirely removed by disengaging the snap 10 and may be used temporarily as an ordinary billfold.

Although I have illustrated the embodiment of my invention which I believe to best illustrate the same, it will be readily understood that various changes coming within the spirit of my invention may suggest themselves to those skilled in the art, and hence I do not wish to be limited to the specific form shown or uses mentioned except to the extent indicated in the appended claims, which are to be interpreted as broadly as the state of the art will permit.

I claim:

1. A letter wallet comprising a substantially rectangular letter file including a pair of sides secured together along two adjacent edges, a billfold, and friction snap means positioned adjacent the juncture of one of said closed edges and an open edge for pivotally and detachably securing said billfold to said letter file.

2. A letter wallet comprising a pair of opposed sides connected together along a folded edge, said sides being closed together along an edge adjacent said folded edge, a billfold having a folded edge, and means securing the ends of the same together to provide a pocket, and friction snap means positioned adjacent the juncture of said closed edge and one open edge pivotally and detachably connecting said billfold and said letter file to support said billfold with said pocket opposing said folded edge of said billfold.

MARTIN E. TROLLEN.
